UNITED STATES PATENT OFFICE

2,381,195

PIN CURL HAIR ROLLER

Henry Clay Whittaker, Memphis, Tenn.

Application January 29, 1944, Serial No. 520,302

1 Claim. (CL 132—34)

The invention relates to means for preparing what are known as "pin curls" in the hair dressing art, which consists of a large number of biscuit-shaped windings of narrow strands of hair, which are set in various ways in such windings, and when, thereafter drawn out or allowed to fall beside the head, they form spiral curls, in distinction to wavy effects produced by other forms of hair shaping and setting procedure.

It is an important aim of the invention to provide a simple implement by which the hair may be quickly wound into the necessary coils by which the curls are formed, and which may be removed from the coils after the coils are supported in place upon the head during setting by means of pins or otherwise, thus requiring no retention of a forming device in the coils while the hair is being properly set.

A further important aim of the invention is to present such an implement which may be produced at extremely low cost, which will be highly efficient in function and liable in a minimum degree to derangement by breakage, wear, or other deterioration incident to ordinary use.

A further aim of the invention is to present such an article which may be manipulated by inexperienced persons with a minimum liability of mistakes or misformation of the hair, as well as involving a minimum likelihood of injury to the hair or the person.

Another aim is to present a hair shaping device of this kind which may be operated with great rapidity in forming the hair, so that a minimum of time is required in completing a coiffure.

A further purpose is to enable the production of the article from a wide range of materials readily available so that it will function effectively, whether made of one material or another.

Additional objects, advantages and features of invention reside in the construction, arrangement and combination of parts involved in the embodiment of the invention, as will be more readily understood from the following description and accompanying drawing, wherein

Figure 1 is an elevational view of the implement.

Figure 2 is an end view thereof.

Figure 3 shows the device in use with a strand of hair in course of winding.

Figure 4 is a similar view showing the final movement in the winding and positioning of the device with respect to the head of the user.

Figure 5 shows the procedure in removal of the hair coil from the device.

Figure 6 shows the final stage in the formation and securement of the coil, so that the implement may then be removed.

There is illustrated a hair winding and shaping device comprising a spindle member 10, having a rounded flange at 11, on the upper extremity, the lower portion slightly over one-half its length in the present instance being longitudinally slotted as at 12, the slot opening on 10 the extremity of the spindle, and being flared at its outer end, as at 13. The extreme end portions 14 beside the slot may be slightly curved outwardly, as shown, for retention of a hair ejector device, to be presently described.

15 In the form of the spindle as thus described, it resembles ordinary clothes pins in some degree, with the exception that it must be rectilinear on its external surface, longitudinally of the device, and the slot 12 therein stops at a somewhat greater distance from the head flange 11. Slidably engaged upon the spindle and snugly fitted thereto, there is an ejector sleeve 15, of a length slightly less than the distance from the flange 11 to the inner end of the slot 12, although if desired, it may be of a length equal to or slightly greater than that distance without impairing the function of the device. Upon its inner end a planiform flange 16 is 20 formed, having a diameter considerably greater than that of the spindle 10, and preferably much greater than the maximum diameter of a hair coil wound on the device, as will be described.

25 In practice, I have made the spindle 10 with an external diameter of approximately three-quarters of an inch, and a diameter of the flange 16 approximately an inch and a half, although the device may be much larger without modifying its function, and it may be found desirable to provide various sizes to suit the requirements 30 of the users. The length of the sleeve 15 may be approximately one inch or more, and the total length of the spindle in one form may be approximately three inches or slightly more.

35 The spindle and sleeve are adapted to be produced from many of a number of materials, including metal, plastics (including glass), or wood. In the event that it is formed of wood, a very hard wood should be employed, with a minimum liability of formation of splinters or cracks into which the hair might engage or become entangled.

40 The elements of the device may be either molded or turned and cut from stock materials, and when formed as illustrated and described, the sleeve 15 may be engaged upon the spindle by

pressing the tips 14 together until the divergent parts may be entered in the sleeve, after which the sleeve is pressed longitudinally inward upon the spindle, the points then separating sufficiently to prevent accidental withdrawal of the spindle, as will be understood. This will permit the sleeve to be thrust longitudinally outward beyond the tips 14, but the latter will engage frictionally within the sleeve, so as to hold it against accidental slipping from the spindle, unless it is completely removed manually.

In the use of the device, the sleeve 15 is pressed longitudinally inward upon the spindle until it is against or close to the head flange 11, after which a strand of hair is drawn outwardly from the head of the user, and the slot mouth 13 presented so as to receive the tip end with the strand therein, the strand being then moved to the inner end of the slot 12, or close thereto. The spindle is then rotated on its longitudinal axis so as to wind the strand of hair completely thereon, and in the latter part of this movement, the spindle is upended or otherwise moved to present it in a position approximately normal to that portion of the scalp at the base of the strand. The sleeve 15 is then pressed outwardly longitudinally against the hair wound upon the spindle, as shown in Figure 5, and this movement is continued until the hair is pressed snugly against the head of the wearer, as shown in Figure 6, whereupon a hairpin 17 or a plurality thereof is engaged in the biscuit-type shaped coil of hair thus formed, so as to hold it against unwinding and to maintain it snugly against the head of the user. In the pressing of the coil against the head as shown in Figure 6, the spindle should be held outwardly, so that it is not thrust against the head or scalp of the user, but so that it is drawn upwardly within the sleeve 15, and after emplacement of the hairpins the implement may be removed from its position and the winding operation repeated with another strand of hair, as above described. These operations are repeated until all of the hair is coiled which it is desired to shape into the pin curls, and the number of operations will be dependent upon the quantity of hair which is included in each strand wound upon the device.

Either before or after the winding of the hair, it may be wetted with any suitable hair setting materials or otherwise treated, so as to preserve the coiled hair after the hair has been held in place for a proper length of time.

The manner of retaining the hair in position upon the head, and of treating it for attaining the desired curls will be readily understood by those versed in the art, and need not be discussed at length.

I have shown and described my invention in the best form known to me with great particularity, but it will, nevertheless, be understood that various modifications in the construction, arrangement and sizes of the parts, as well as substitution of materials and mechanical equivalents may be made without departing from the spirit of the invention, except as more specifically limited by the appended claim.

20 It should be understood that the material used in the spindle 16 is preferably of a resilient nature, so that the flexing of the slotted end portion may be effected manually, under the operation of the sleeve 15 as described, and in the event that the spindle is made of metal, it will be found practicable to use a stock steel tubing, preferably of the non-corrosive or non-rusting type, and when this is slotted and shaped as described, the forked portion may be readily flexed manually.

30 I claim:

A hair-shaping device comprising a spindle member having a longitudinally slotted hair-receiving end portion, a sleeve thereon having a flange at its outer end, said spindle being formed 35 with a flanged head portion at the end opposite the slotted end portion, the extremity of the slotted end portion being flared, for the reception of hair strands therein, and the ends of said spindle adjacent the slot being extended divergently outwardly away from the slot for retention 40 of said sleeve against casual disengagement, and compressible toward each other, permitting removal of said sleeve.
